UNITED STATES PATENT OFFICE.

R. L. HAWES, OF WORCESTER, MASS., ASSIGNOR TO ROBERT RENNIE.

IMPROVEMENT IN MACHINES FOR DRESSING LAWNS.

Specification forming part of Letter Patent No. 12,771, dated April 24, 1855.

To all whom it may concern:

Be it known that I, R. L. HAWES, of Worcester, in the county of Worcester and State of Massachusetts, have invented a new and useful Machine for the Purpose of Dressing and Finishing Lawns, of which the following is a full, clear, and exact description, reference being had to the annexed drawings, making part of this specification, in which—

Figure 1 is a plan of my machine; Fig. 2, a side elevation of the same; Fig. 3, an end view, and Fig. 4, details which will be referred to hereinafter.

The goods generally known as "lawns" require a peculiar flexibility of texture, which is imparted to them during the finishing process by stretching or straining them diagonally in opposite directions, so that the weft and warp threads are caused to cross each other at acute angles, first on one side, then upon the other of the perpendicular, by which operation, which is performed after the starch has been applied, and while the goods are being dried, the weft and warp threads are prevented from being so rigidly starched together as would otherwise be the case, and the fabric acquires the peculiar finish and texture required.

To accomplish this end and to perform the operation expeditiously and effectively is the object of my present invention, which consists of a peculiarly-contrived machine, in which, while the goods are being drawn over the surface of a heated cylinder, the selvages, in lieu of being moved simultaneously, as in ordinary finishing-machines, are caused to advance and remain at rest alternately, each one remaining motionless while the other moves on, by which means, while the goods are rapidly dried and finished, the peculiar flexibility required is imparted to them, the warp and weft threads being sized, but not rigidly starched together, as is the case with ordinary starched and finished goods.

To enable others skilled in the art to understand and use my machine, I will proceed to explain its construction and operation.

In the accompanying drawings, A is the frame-work of the machine; B, a stationary drying-cylinder, heated by steam passing through its hollow bearings C. Over the surface of this stationary heated cylinder the goods are passed in the following manner, the selvages being led along alternately, one

remaining stationary while the other is in motion:

D are metallic hoops or rings, which surround the drying-cylinder. These hoops carry the teeth x, upon which the fabric is stretched, and are made adjustable to a greater or less distance from each other, in the following manner:

E E' are circular metallic disks, which are allowed to revolve upon the hollow bearings C. a are spokes projecting from these disks, and carrying the screwed arms b, which are caused to project more or less in toward the cylinder by the nuts c, by which they are also secured in position. These arms b are secured at their inner ends to the hoops D, which are adjusted in position by means of the nuts to suit the different widths of cloth to be operated upon.

To the disks E E' and the hoops connected with them an alternate intermittent rotary motion is communicated in the following manner:

F is a shaft carrying the eccentrics G G', which are set to throw in opposite directions, as seen in Fig. 2. These eccentrics are connected by means of sharps d to the rods ff, the ends of which hook over pins e e', projecting from the radial arms H H', which vibrate freely upon the hollow bearings C.

g are pawls upon the end of the arms H H', which operate upon the inclined teeth h, projecting from the face of the disks E E'. When the arm H moves in the direction of the arrow, Fig. 2, the pawl g, striking upon one of the teeth h, carries the disk E and hoop D a certain distance. When the arm H moves in the opposite direction, the pawl g slips over the teeth h, and no motion is communicated to the hoop D. As the throw of the cams G G' is one hundred degrees apart, it is evident that while one of the hoops D is advancing the other will remain stationary. The selvages are thus moved alternately, and it is evident that there must be a corresponding alternate take-up motion to deliver the fabric from the machine. This is effected in the following manner:

I is a roll formed of sections i, which are allowed to revolve independent of each other. Over this roll the fabric passes out of the machine.

K is a stationary shaft, on which revolve two roller k k'.

l l' are sleeves, which, together with the pulleys *m m'*, also revolve upon the shaft *K*. A rotary motion back and forth is communicated to the sleeve *l* in the following manner:

p is a cord attached at one end to the vibrating arm *H* and at the other to the spring *q*. This cord passes once or more round the pulley *m* upon the sleeve *l*, and thus as the arm *H* vibrates the sleeve is rotated back and forth by the cord *p*, which passes round its pulley. From this back and forth motion of the sleeve an intermittent rotary motion is communicated to the roller *k* in the following manner:

o is a tooth, Fig. 4, upon the end of the sleeve *l*, which engages with the spring pawl *n* upon the end of the roller *k* when the sleeve revolves in one direction, and the roller *k* is caused to rotate with the sleeve. When the latter revolves in the opposite direction the roller *k* remains stationary, the tooth *o* passing freely round without engaging with the pawl. One of the selvages of the fabric, as it leaves the machine, passes between the roller *k* and one of the sections *i* of the roll *I*, Fig. 2, and as the roller *k* revolves intermittently the selvage is alternately drawn off and suffered to remain at rest. Upon the other side of the machine there is a corresponding apparatus, *p' q' m' l' k'*, for the purpose of operating upon the other selvage, and the parts are so adjusted that when the hoop carrying one selvage is in motion that selvage is at the same time being drawn off the machine by the apparatus just described. The fabric is stretched and tentered upon the hoops *D* in the following manner:

L L' are adjustable slides, which carry the inclined pin-wheels *M M'*. These wheels are allowed to revolve freely upon their pivots *r*. The pins *y*, which project radially from their periphery, are secured firmly thereto in any suitable manner:

Operation: The goods enter the machine over the bar *P*, the selvages being put upon

the pins *y* of the wheels *M M'* at a point, *s*, where these points approach nearest to each other. As the wheels *M M'* revolve, the points continually recede from each other, (as will be apparent from an inspection of Figs. 1 and 3) until they interlock with those upon the hoops *D*, to which the fabric is transferred, as seen at *t*, Fig. 1, the brushes *N N'* pressing it down, as before mentioned. The hoops *D* are now caused to make one-eighth of a revolution, more or less, alternately, by which means the diagonal working of the threads upon each other before spoken of is attained, and the rigid adhesion of the warp and weft threads with each other is broken, which gives to the material that pliancy peculiar to fabrics of this description.

Cylinders of felt have been made use of for the purpose of pressing the fabric down upon the teeth of the hoops *D*. These are very soon destroyed, and are liable to other objections, which it is the object of the brushes above referred to to remove.

I do not claim finishing lawns by causing the selvages to advance alternately as the goods pass through the dressing-machine, as this is done upon the machine described in Newton's London Journal, cojoined series, volume 32, page 77; but

What I do claim as my invention, and desire to secure by Letters Patent, is—

1. The stationary heating-cylinder, in combination with the hoops *D*, having an alternate intermittent revolving motion, in the manner described, and for the purpose set forth.

2. The sectional roll *I*, in combination with the rollers *k k'*, operating substantially as described, for the purpose of drawing the selvages alternately from the machine, as set forth.

R. L. HAWES. [L. S.]

In presence of—

T. W. HAMMOND,
L. W. HAMMOND.
